COMPUTING APPARATUS

Charles J. Goodale, Springfield, Mass.

Application June 8, 1953, Serial No. 360,121

37 Claims. (Cl. 235—61.8)

The present invention relates to computing methods and to machines capable of carrying out such methods wherein mechanical movements may be largely replaced by electronic devices. This application is a continuation in part of the copending application Serial No. 678,152 filed June 20, 1946, now abandoned.

Some of the main objects of the invention are to provide an improved method of carrying out algebraic summations by means of scale elements which method can be carried out by simple manual aids as well as by automatic computing machinery, and to provide computing apparatus which, controlled by a record moved therethrough, performs quickly and reliably mathematical operations, especially such summations, as indicated by indicia applied to the record.

Other objects of the invention are to provide an accounting machine which performs its operations in simple and yet reliable manner, unhampered by requirements introduced by complicated counting and accumulating procedures and accordingly more or less complicated mechanical gear; to provide a computing machine which materially reduces the length of time between the recording of collected data, and the evaluation thereof at the same or another place; to provide a computing machine which is composed of operating units which are only electrically interconnected, so that they can be easily rearranged and combined to form complete machines suitable for various purposes; to provide apparatus of this type which furnishes final data without any preliminary or subsequent sorting operation of the records from which this data are collected and without the necessity for highly manual preparatory work, which sorts automatically by way of a source recorder or subordinate unit, and which furnishes these data in a minimum period of time from the first recordation thereof; and to provide computing apparatus of this type which eliminates any need for reading, copying, or transcribing steps intermediate the initial collecting of the data concerned, and the final evaluation thereof.

Further objects of the invention are to provide fully effective and reliable apparatus for defining and putting into effect the shifting reference principle used according to my above-mentioned improved computing method, to provide effective and simple apparatus for translating accumulated data into a visible record, to control the computing operations of the machine by means of counting and operational indicia and sequence indicia combined in a manner which renders these operations speedy, reliable and practically independent of irregularities of the indicia, and to provide electrically controlled and actuated means for shifting counting elements, for operating contact controlling elements, and for operating printing mechanisms in a particularly simple and effective manner.

In one of the aspects of the invention, algebraic summations are carried out by defining digits of a notation which may also be referred to as series of numbers by scales of equal, digit indicating steps, and by shifting

these series in the same sense, whereby the shifting of one series adds, and shifting of the other series subtracts digits defined by the amount of shifting; the relation of the two series may be indicated by a zero or home indicating point of one of the two series which home point shifts or floats with its series relatively to fixed instrumentality to which both series can be shifted, the zero point alone being used for computing whereas the fixed instrumentality itself is not used for purpose of computing. The digit or number series of the notation may be defined by straight or circular scales which can be shifted in one direction, the same for both scales, relatively to a support represented by the fixed instrumentality.

In another aspect of the invention, the above objects are attained by coupling one or the other of two counting members to an actuating means which is adapted to advance stepwise in a given direction under the control of sequence indicia, and under the control of means for coupling one or the other counting member to the actuating means under control of and during steps determined by counting indicia conjointly with the sequence indicia, means being in addition provided which are controlled by operational indicia for selecting one or the other of the counting members for coupling by means of the counting indicia to the sequence indicia actuated stepping means; one of the counting members is provided with means, such as electric contacts which are part of a relay circuit, for indicating the relative position of the two counting members independently of their position regarding the machine considered as a mechanical structure.

Additional features of the invention include magnetically controlled movements which serve as clutching and switching elements and operate by shifting a coupling member from a permanent magnet fastened to one of two relatively movable elements to an electrically controlled magnet fastened to the other element which may be a rotatable shaft; commutator switches with circular contacts whose angle relation conforms to the operational relation of the above mentioned counting members and permits a wide range of correlation of computing operations as controlled by the record indicia; an arrangement for printing computation results by means analogous to the accumulating means; switching means, controlled by operational indicia, for setting up circuit connections which selectively induce various computing operations such as adding and totalling as herein described in detail, but also subtracting, carrying over, printing and resetting; and various photo-electric and control element supervised electron tube circuits which, in conjunction with timing and energy storing networks, perform many of the essential functions of the present computing apparatus.

These and other objects, aspects and features will appear from the following description of a typical practical embodiment illustrating the novel characteristics of my invention. This description refers to drawings in which

Fig. 20 is a circuit diagram of the electrical apparatus incorporated in the herein described embodiment of my invention; and

Figs. 21, 22 and 23 are diagrams illustrating the improved computing procedure according to the present invention.

Apparatus according to the present invention lends itself very well to unit construction and to the assembly of unit elements, each performing its particular function, in operational combinations and spatial set-ups selected according to individual requirements. While the embodiment herein described represents a machine that performs operations satisfying average computing requirements, it should be understood that it can be used as an element of apparatus fulfilling different, perhaps more elaborate, requirements and that its units and elements can be employed in combinations other than that herein referred to.

The apparatus now to be described incorporates assemblies which will be referred to as scanner, accumulator, recorder, and circuit units. These units may be incorporated in a cabinet such as shown in Fig. 1 which indicates at 30 the housing proper, screwed to a base plate 31 which is also shown in Fig. 4. The cabinet has a feeding platform 32, and doors 33 and 34 permitting access to the various units. Fig. 1 indicates by way of dot and dash lines how the above mentioned units or components of the machine may be distributed within the cabinet 30, I indicating the detecting unit, II the accumulator unit, III the recorder unit, and IV the circuit unit. These units will be taken up in the above indicated order, but before explaining the detector or scanning unit, a record means suitable for purposes of the invention will be described.

Record

As indicated in Figs. 2 and 3, a suitable support 40, preferably in the form of a strip or tape, carries counting or numerical marks 41, operational marks 42, and sequence marks 43. These marks, whose respective significance will be presently described, or indicia may be applied by means of a recording machine such as described with reference to Fig. 29 of my patent No. 2,251,998 of August 12, 1941. If desired, the sequence marks 43 may be initially applied to the strip 40, and the counting and operational marks added in proper register with the sequence marks in the manner to be explained below.

The counting marks or generally speaking digits of a notation are in this embodiment of the nature of code element indicia, such that for example one or a selected combination of four marks of one column of a number group define one digit of the notation. The strip shown in Fig. 2 records numbers having up to five digits. The uppermost group of Fig. 2 represents the number "56789" in the manner also shown in Fig. 3 which carries nine code mark columns arranged so as to indicate the manner in which the nine digits are defined. Each digit is made up of four marks arranged in a column and the digit column position defines the digit order or decade. Each individual code mark defines a certain numerical value, in the present example values "2," "2," "1," and "4." Thus, the digit 1 is defined by the code mark "1" having the third position in its column, digit 2 is defined

by the first mark "2" in the respective column, digit 3 is defined by the code marks "2" and "1," digit 4 is defined by code marks "2" and "2," and so on, as clearly indicated in Figs. 2 and 3. It will further be noted that these marks are not particularly distinguished except as to position in their respective columns, each column of course defining, as pointed out above, the positional or order value of its respective digit. As mentioned above, the marks of Fig. 2 permit the recording of numbers with five digits, whereas a strip having nine columns as that in Fig. 3, would permit the recording of nine digit numbers. It will be understood that digit 2 may be defined by the second mark "2" and that indeed any sequence of code mark value positions may be used.

15 As will be noted from Fig. 2, the sequence marks 43 may consist of a continuous black strip containing groups of equally grouped blank spaces or slots which are in register with the code mark rows. Fig. 3 indicates the relative position of code mark elements and sequence 20 marks, the latter being shorter, and within the former. Their relative position is not particularly critical, so long as each sequence mark is within a corresponding counting mark component. In the present embodiment of my invention, a fifth sequence mark 49 is added which 25 has no corresponding code mark row, but is located between consecutive code mark groups defining respective numbers.

Any number of operational indicia 42 may be applied to the strip, their significance being defined by their lateral 30 position on the strip. Thus, mark 45 has a meaning different from that of mark 44, and any required number of similar marks may be applied between the code marks and the strip of sequence marks. In the present embodiment of my invention, a code mark group 48 35 covering the entire code mark area always goes with the mark in position 45, for reasons which will appear hereinbelow.

These marks may be applied in any suitable medium, the only requirement being that they affect a selected 40 type of radiation, visible or invisible, differently from the matter in which it is affected by the record carrier proper. Thus, the marks may be applied in printers' ink or stamp ink, when they will reflect light to a much lesser degree than the fairly smooth and light surface 45 of the clear record strip of paper, Celluloid or other material.

The above mentioned significance of the code mark values, namely "2" "2" "1" "4," and this sequence of the values, are not unique, other combinations being quite 50 feasible, as for example "5" "1" "3" "2." The significance of this particular arrangement of the record strip indicia in view of the computing apparatus according to the present embodiment of my invention will be explained more in detail hereinbelow.

Detector

As mentioned above, the scanning or detecting unit of the machine is contained in compartment I of the cabinet shown in Fig. 1. As indicated in Figs. 4 and 6, it carries 60 the record strip 40 on two rolls or reels 51, 52, one of which, for example 52 may be suitably coupled to and driven by the motor 55 of a type appropriate for this purpose. The strip 40 is guided by two idling rolls 56, 57, along the underside of a scanning plate 60 having a scanning opening 61, and therebelow a platform 62 which flattens the record strip 40 as it passes the scanning window 61. Reels 51, 52 and rolls 56, 57 are journaled in bearing brackets 64, fastened between unit base 36 and plate 60.

70 Brackets 65 (Fig. 4) support two scanning units 66, 67 on plate 60. The scanning units have housings 68, 69 with cover plates 71, 72 and perforated walls 73, 74, which support light conducting rods 70, 80, leading from the interior of the respective scanning housings to the scanning window 61. The scanning terminals of these

light conductors may have reduced diameters, as indicated in the figures, in order to accommodate them to the approximate magnitude of the indicia elements of strip 40. As indicated in Fig. 5 as related to Fig. 2, the scanning rods are placed opposite the various indicia columns of the record strip 40. By shaping the light conducting rods as indicated in Figs. 4 to 6, it is possible to reduce the dimensions of the marks and hence of the record strip to any desired degree.

The scanning unit 67 carries within one compartment 81 (Figs. 4 and 6) several photo-electric tubes P_d , and a flash lamp F. The number of photo-electric tubes P_d in compartment 81 (in this instance seven) corresponds to the number of code mark order columns and operational mark positions or columns and hence to the number of light conducting rods leading into this compartment, whereas only one flash lamp covers the entire series of conducting rods, which, as indicated in Figs. 4 and 6 terminate directly in front of the flash lamp. The photo tubes P_d in compartment 81 are so arranged that each of them receives considerable light flux when lamp F radiates. A second compartment 82 separated from compartment 81 by an opaque wall 85, contains a light source E which is associated with a light conducting rod 91 arranged similar to those leading into compartment 81.

Scanning unit 66 (Figs. 4 and 5) likewise has two compartments, namely 83 and 84, separated by opaque wall 86. Compartment 83 contains seven photo-electric tubes P_i so arranged that each of them can receive light from a coordinated light conducting rod 70, but not from any other rod. The compartment 84 contains a photo-electric tube P_i associated with a light conducting rod 92.

The light conducting rods leading into scanning units 66 and 67 respectively, are so placed and inclined that the rods 80, 91 emerging from unit 67 direct light beams onto the respective mark series of recording strip 40, whereas the light conducting rods 70, 92 leading into unit 66 are adapted to receive light which might be reflected into them by the bare and comparatively clear surface of the record strip, where it is not covered by recording material.

The various photo tubes will be further identified with reference to the circuit diagram of Fig. 20.

Accumulator

The accumulator unit which may conveniently be arranged in compartment II of Fig. 1 is mounted on base board 101 which may be fastened to the main base plate 31 of the cabinet, and has side frame boards 102 and 103, as indicated in Figs. 7 and 8 which together constitute a single view, partly in section, of the accumulator assembly. The movable portions of the accumulator are guided upon or fastened to a shaft 105 which is journaled in frame walls 102 and 103 by means of ball bearings 108 and 109.

The shaft 105 can be rotated in steps of prearranged magnitude, by means of stepping or sequence solenoids Z1, Z2, Z4 (Figs. 7 and 9) each of which consists of a magnet winding 111 and a housing 112 fastened to plate 101 by brackets 128. Into housings 112 are screwed holding plates 115, which secure the coil within the housing, and also determine, by means of rims 116, the travel of armature plungers 118 which are by means of rods or links 119 and one way couplings 120 joined to shaft 105. As shown especially in Fig. 10, couplings 120 may be ball clutches consisting of two bearing rings 121, 122, and therebetween a clutch ring 123 which has a cam recess 124 confining a ball 125 between its face and the shaft 105. As well known, the clutch body will be attached to shaft 105 only when it rotates in the direction indicated by the arrows of Figs. 7 and 10, whereas the shaft is released when the clutch body is rotated in the opposite direction. Thus, the shaft 105 is rotated through steps corresponding to the stroke of each respective plunger if the latter moves in the direction of the arrow 75

of Fig. 9. It will be observed that rotation of shaft 105 by solenoid Z1 will not affect the other solenoids whose one way clutch will then be idle, and vice versa. As indicated in Fig. 9, the strokes of solenoids Z1, Z2 and Z4 are stepped in the ratio 1:2:4. The plunger of solenoid Z2 floats, but its length is so selected that, when de-energized, it permits the plunger of solenoid Z4 to assume its full stroke, whereas when Z2 is energized, its plunger advances to an extent which presets the stroke of the plunger of Z4 to one-half of its full value. Hence, (a) the stroke of solenoid Z2 pushing the plunger of de-energized solenoid Z4, (b) the stroke of solenoid Z4 as preset by solenoid Z2, (c) the stroke of solenoid Z1, and (d) the normal stroke of solenoid Z4 as shortened by the previous stroke of solenoid Z2, bear the ration relation of 2:2:1:4. As will be fully explained hereinbelow, these strokes are effected by appropriate circuit control, their four values correspond to those of the four counting code marks discussed above with reference to Figs. 2 and 3, and they permit the definition of any one of the nine digits in any decade position.

The accumulator unit further contains a number of digit counter sets which are in this art sometimes also referred to as accumulator sets, one for each order or position. Only two of these sets are shown in Fig. 7, namely the "units" and "tens" counter sets. Each counter set consists of two permanent magnets 131, 132, which have bores permitting shaft 105 to rotate freely therewithin, and which are fastened to base plate 101 by brackets 134. Fixed to shaft 105 are core bodies 135, 136 of magnetic material. Solenoid coils Za and Zs, mounted on brackets 165, surround core bodies 135, 136 and define gaps 160. Rotatably connected to shaft 105 by means of ball bearings 141, 142 are two clutch sleeves 143, 144, each of which carries a commutator disk, indicated at 145 and 146, of insulating material, and has a coupling slot, indicated at 155, 156, compare also Fig. 11.

These commutator disks carry, riveted or otherwise fastened thereto, five concentric contact sectors s1, s2, s3, s4, s16 and companion sectors s11, s12, s13, s14 and s15 as indicated in Figs. 13, 14 and 15. The contact sectors of the respective commutator disks are in sliding contact making engagement while in coinciding angular position. It will be noted that Fig. 13 is a view seen from the right hand side of Fig. 7, whereas Fig. 14 is a similar view seen from the left hand side of Fig. 7; Fig. 15 shows the commutator contacts of both disks in super-imposed position, seen from the left hand side of Fig. 7. As indicated in Fig. 13, the angular distance between the extreme ends of the commutator contacts s1, s2, s3, s4, s16 of disk 145 is 36° , that is $\frac{1}{10}$ of the entire circumference, and corresponding to a step of value "1." Ten equidistant points of the circumference of this disk define ten digit positions, from 0 to 9, as likewise indicated at Fig. 13. The ends of the contact segments s11, s12, s13, s14, s15 of commutator 146 are similarly defined, as indicated in Fig. 14. The respective disks 145 and 146 rotate, when coupled to shaft 105, in the same direction, as indicated by the arrows applied to the respective figures.

Between permanent magnets 131, 132 and cores 135, 136 are arranged coupling slides 151, 152 which have two claws or prongs 153 engaged in the above mentioned slots 155, 156 of clutch sleeves 143, 144. The last mentioned two elements are isometrically shown in Fig. 11. The two slots 155, 156 engage the two claws 153 permanently, although the latter can move axially therewithin, so that, when coil Za is de-energized, disk 151 is attracted to permanent magnet 131 retaining sleeve 143 immovable with regard to the frame. On the other hand when coil Za is energized, the attractive force of the permanent magnets is overcome and disk 151 is attracted by core 135, which, it will be remembered, is fast to shaft 105, so that claws 153 will now move sleeve 143 with them. In the first mentioned instance, namely with disks 151 or 152 fast to permanent magnets 131 or 132 (which are

mounted on the apparatus base), sleeve 143 or 144 are fixed relatively to the base but permit rotation relatively to shaft 105 on ball bearings 141 and 142; in the last mentioned instance, namely when coils Za or Zs are energized, shaft 105 and disks 143 or 144 rotate together. As will appear hereinbelow, Za and Zs are never simultaneously energized.

On radii corresponding to those of the commutator segments s1 to s5 and s11 to s15, are arranged, on the outside of disks 145 and 146, collector slip rings 170 which are conductively connected to the commutator segments, for example by the above mentioned rivets. These rings cover uninterruptedly the entire 360° arc of the disks, and continuously contact individual brushes 180, as indicated in Fig. 7.

As mentioned above, the accumulator has a counting set for each digit position; in the present five sets would be provided although only two are shown in Figs. 7 and 20.

The accumulator also has several relay units, which are shown in Fig. 8.

The switching elements of these relays may assume various forms, whereas their actuating structures are essentially similar, as will now be explained with reference to Fig. 8. This figure indicates at 171 and 172 permanent magnets which are fastened to base 101 by means of brackets 175 and 176. Core supports indicated by numeral 181 are fastened to base 101 with brackets 185 and have guiding slot portions 186. They carry contact bases 187 of insulating material. Coils Zup, Zos and Zoc are fastened to base 101 by means of brackets 165 and form gaps 195 with cores 192 of magnetic material that are fastened to core bodies 181. Within the gaps 195 move contact carriers 194 which are similar to the coupling elements shown in Fig. 11, with the difference that one claw or if desired each claw carries contact 198 or contact bridges 199. As indicated in Fig. 8, there may be contact bridges on either side of the movable claw of switch element 197, or one or several contact pairs to be connected by these bridges, may be arranged on one or either side of the movable claw. The various contacts shown in Fig. 8 are not individually identified because they correspond to those identified and described in detail with reference to the circuit diagram Fig. 20. It will now be evident that energization of coils Z moves the switching bridges such as 194, 197 in the direction of the axis of shaft 105, while de-energization causes them to be attracted by the permanent magnets. This mode of actuation is quite similar to that of the accumulator and commutator sets, and permits use of similar parts for both types of mechanism.

It will be evident that various clutches and switches can be constructed in similar manner, in accordance with varying circuit requirements, and arranged in compact units as indicated by Figs. 7 and 8.

Recorder

The recorder unit is arranged in the compartment indicated at III of Fig. 1. It is mounted on a base plate 201 and on frame walls 202, 203 and 204 (Fig. 16), with the base plate 201 secured to the main base plate 31 of the cabinet. In a space formed by walls 203, 204 and by a printing base plate 206 is mounted a printing device with a hammer solenoid Zh which is adapted to lift, when energized, a printer hammer 211 against the underside of recording card 200, inserted through slot 212 (Fig. 1) between guides 215 and 216. As indicated in Fig. 1, the stepped upper portions of cabinet compartments I and II form a feeding platform 32 provided with indicating lines 219, which permit registration of the card 200 with the printing mechanism. The card may be discharged through slit 220 in the rear wall of the cabinet, indicated in dotted lines in Fig. 1. An ink ribbon 221 carried by rolls 222 and 223 supplies printing medium in well known manner. When hammer 211 is

lifted, it presses card 200 against ribbon 221 and the type wheels to be described hereinbelow, thus recording the number defined by the type wheel digits.

A shaft 205 is journalled in side walls 202 and 203 by means of ball bearings 228 and 229. This shaft performs a function similar to that of the above described accumulator shaft 105 and can be rotated stepwise by means of solenoids Zp1, Zp2 and Zp4 which are in the present embodiment identical with the accumulator solenoids Z1, Z2, Z4 described with reference to Figs. 7 and 9, and advance the shaft through the corresponding steps of 36°, 72° and 144°. In order to simplify Fig. 16, only one solenoid Zp4 with its clutch 120 is shown.

The shaft 205 is further associated with a number of 15 clutch elements, one for each order or position, which are similar to those described with reference to Fig. 7, with the only difference that they are equipped with gear wheels 231 in addition to the commutator disks 233, and that stationary commutator disks 235 are fastened to 20 the energizing coils Cp. It will be noted that gear wheels 231 rotate whenever coils Zp are energized while shaft 205 turns, coupling the bearing supported switch and gear wheel sleeves 238 to cores 242 which are fixed to shaft 205. This also provides selective rotation of the 25 commutator disks 233.

The stationary commutator disks 235 have two concentrical contact rings s22, s23 with gaps extending through 36°, as shown in Fig. 17, while the rotatable disks have two contact segments, s25, s26, covering an 30 angle somewhat smaller than 36°, as shown in Fig. 18. Fig. 19 shows the two disks in superimposition. The arrows applied to Figs. 16, 18 and 19 indicate the respective directions of rotation, it being assumed with respect to Figs. 18 and 19 that these figures show the contact 35 faces of the disks of Fig. 16. The contact elements of these commutator switches are also shown in Fig. 20 and their function will be further explained with reference to that figure.

A supporting rod or stationary shaft 245 is fastened 40 to frame walls 202 and 204 and carries several hollow shafts, one for each type wheel and hence one for each order position which the machine in question is required to handle. In the present instance five type wheels 251 to 255 (corresponding to the five digit positions of Fig. 45 2) are shown which are correspondingly fastened to hollow shafts 261 to 265. Each type wheel is supplied with raised type numbers 0 to 9, opposite the above mentioned ribbon 221. The other ends of shafts 261 to 265 are fast to gear wheels which mesh with the gear wheels 50 231 of the printer clutch units. Fig. 16 shows only two of these gear wheels, namely 271 and 272; it will be understood that each type wheel has one of these gear wheels which again are associated with the appropriate number of clutching and commutator switching units, 55 each with permanent magnet 241, core 242, coil Zp, commutator disk 235 and rotatable sleeve 238 with gear wheel 231 and commutator disk 233.

It should be noted that the digit numbers of the type wheels run in reverse direction as compared to those of 60 the accumulator wheels (as indicated in Fig. 13), having in mind the respective sense of rotation of these elements.

Circuit

65 The complete circuit diagram of a computing machine incorporating the various features of the herein described embodiment of the present invention is shown in Fig. 20.

In Fig. 20, the terminals a, b of a standard alternating current supply system feed through a suitable transformer into terminals h to which the heaters of all electron discharge tubes of the system may be connected. Through another transformer the alternating current system energizes the lamp E which is the detecting lamp shown in Fig. 6 in compartment 82 of scanning unit 67. The alternating current line a, b further supplies a recti-

fier indicated by tube V_r and filter N_r , which supplies the bias for tube G_f , in the manner to be described hereinbelow, through tap 301 which is less positive than terminal a . The main supply of direct current for operating the circuit is indicated by positive bus A and negative bus B.

A sequence detecting and flash initiating network N_f includes a photo tube P_t whose anode is connected to bus A and whose cathode is connected through resistor R_1 to bus B. A gaseous discharge tube G_f having a control electrode g_f is connected with its cathode to B and with its anode to a point 302 between a resistor R_2 and a capacitor C_1 . Resistor R_2 and capacitor C_1 are connected in series between buses A and B. A flash lamp F is connected between tube G_f and point 302, in series with a resistor R_2 . A resistor R_3 is connected in parallel across lamp F of conventional gaseous flash discharge type.

The above mentioned lamp E is arranged for illumination of photo tube P_t , through the light conducting rods 91 and 92 shown in Figs. 5 and 6. The lamp F is arranged for direct flash illumination, in the manner described below, of a series of photo tubes P_d contained in scanning unit 67, as shown in Figs. 4 and 6, and for indirect illumination, through the light conductors 70, 80, of a series of photo tubes P_i contained in compartment 83 of scanning unit 66, as shown in Figs. 4 and 5. These photo tube series P_d , P_i are arranged in the clutching and switching tube circuit to be described below, but are in Fig. 20 also represented by single photo tubes P_d , P_i shown adjacent to flash tube F, in order to facilitate understanding of the operation of the circuit. In Fig. 20, the dotted box containing these photo tubes also indicates the direct illumination of tubes P_d and the indirect illumination of tubes P_i through light reflected from the record strip 40 when the light strikes portions of that strip which are not covered by the recording material.

The sequence circuit N_s now to be described contains a number of gaseous discharge tubes G_1 to G_5 , preferably of the hot cathode or thyratron type. One of these tubes is provided for each sequence mark 43 of the record. It will be understood that more than five sequence slit marks may be provided, in which case the circuit will contain additional corresponding thyratrons. The cathodes of the thyratrons G_1 , G_2 , G_3 , G_4 and G_5 , are connected to the negative bus B through resistors R_{11} , R_{12} , R_{13} , R_{14} and R_{15} . The thyratron cathodes are joined through a ring circuit including conductor 303 and capacitors C_{11} to C_{15} . A grid control conductor 304 connects point 303 between the cathode of photo tube P_t and the resistor R_1 , through a time delay network with resistor R_4 and a capacitor C_4 , to condensers C_{21} to C_{25} which lead to the control electrodes g_1 to g_5 of thyratrons G_1 to G_5 . These control electrodes are also connected, through resistors R_{21} to R_{25} , to corresponding sides of the above mentioned ring capacitors C_{11} to C_{15} .

The anodes of thyratrons G_1 to G_4 are connected to the positive bus A through stepping solenoids Z_1 , Z_2 , Z_4 , which are described above with reference to Figs. 7 and 9. Solenoid Z_1 is in the anode circuit of tube G_3 , solenoid Z_2 in that of tube G_1 and solenoid Z_4 in the anode circuits of tubes G_2 and G_4 . In parallel with these solenoids, but connected to an auxiliary bus A_{31} , are printer solenoids Z_{p1} , Z_{p2} and Z_{p4} . The auxiliary bus A_{31} can be connected to the main bus A through the normally open contacts s_{31} of switch Z_{op} which is also shown in Fig. 8 and which will be further described hereinbelow. Between the anode of tube G_5 and bus A_{31} is connected the hammer solenoid Z_h (described above with reference to Fig. 16), and the anode of thyratron G_5 is also connected through conductor A_{32} , which contains solenoid Z_{oc} and normally closed contacts s_{32} of switch Z_{op} , to positive main bus A.

The above described sequence circuit N_s functions as follows:

It will be noted that the grids g_1 to g_5 of the sequence control tubes G_1 to G_5 are connected in parallel and therefore receive together any pulse which becomes effective at conductor 304 of the sequence network N_s due to changed impedance characteristic of photo tube P_t . It is characteristic of this circuit that only one of the several sequence tubes is on at a time, whereas, whenever the circuit receives an impulse, one of the tubes becomes conductive whereas the preceding one becomes extinguished.

Assuming that, for example, tube G_1 is conductive, point 311 on the cathode of G_1 has a fairly high potential (although not sufficiently high to fire tube G_2 through resistor R_{22} and grid g_2) as compared with that of ground B, due to the comparatively small drop across the tube, as compared with that in resistor R_{11} . On the other hand, point 312, associated with the next tube G_2 , has practically the potential of B, because the tube is non-conductive therefore representing an infinite resistance. Due to these conditions, capacitor C_{12} is charged, with the plate next to resistor R_{22} positive and the plate next to point 312 negative. When photo tube P_t receives the next light flash, from lamp E and one of the sequence slits or marks 43 of the record strip, momentarily increasing the potential of wire 304, only grid g_2 of tube G_2 becomes sufficiently positive to render G_2 conductive, because this grid g_2 carries a positive bias due to the above mentioned charge on capacitor C_{12} . With G_2 conductive, point 312 assumes a higher potential. With capacitor C_{12} not yet discharged, point 311 assumes an even higher potential making the cathode of tube G_1 more positive than its anode, so that G_1 extinguishes. Capacitor C_{12} now gradually discharges, whereas capacitor C_{13} charges as above explained with reference to capacitor C_{12} . This cycle continues indefinitely for each potential increase of wire 304, corresponding to a light flash received by tube P_t from exciter lamp E. Each thyratron becoming consecutively conductive in the ring circuit, the solenoids in their respective anode circuits are energized, for purposes to be explained in detail hereinbelow.

When the potential of point 304 increases, due to a flash from lamp E received by photo tube P_t by way of a sequence mark or slit 49, the potential of the control electrode g_f of flash control thyratron G_f is raised, rendering G_f conductive and permitting a discharge of normally charged capacitor C_1 through the flash lamp F, in circuit C_1 —302—F— G_f —B— C_1 . Hence, F delivers an instantaneous light flash for each sequence mark that directs increased light intensity from exciter lamp E to photo tube P_t . As mentioned above, the discharge device V_r supplies the bias for grid g_f of thyratron G_f which is extinguished by the voltage collapse across capacitor C_1 which causes the voltage across tube G_f to go momentarily below its critical value.

For reasons which will become apparent from the following explanation of the operation of the present device as a whole, the sequence control tubes G_1 and G_5 should be triggered after the clutching or counting tubes to be described below have become effective. For this purpose, the above mentioned time delay network with resistor R_4 and capacitor C_4 is provided between points 303 and 304 which introduces a predetermined time delay between the flashing of lamp F and the triggering of the respective thyratron due to the rising potential level of conductor 304.

The circuit according to Fig. 20 further includes a clutching and switching control circuit N_c responsive to the counting and operational marks 41 and 42. This network has a series of pairs of high vacuum discharge devices, which may be separate tubes or contained in the same envelope, as shown in Fig. 20. These tubes

operate on the well known multi-vibrator principle and are indicated in Fig. 20 at V_s , V_p , V_u , and V_t . Tubes V_s and V_p respond to "operational" marks, whereas V_u and V_t operate the counting systems of the accumulator. Tube V_u corresponds to the "unit" order, V_t to the "tens" order, and so on, so that for a record strip with five positions such as indicated in Fig. 2, five counting tubes would be provided. Fig. 20 shows only the tubes V_u and V_t for the first two positions but it will be evident, as indicated by arrows applied to buses A and B and the auxiliary buses, that any desired number of counting tubes can be added. Also, additional operational tubes, corresponding to V_s and V_p , may be adapted.

Each of the operational or counting multi-vibrator double tubes is associated with the conventional timing capacitors, and bias and load resistors. With the grid g_{21} which controls the "off" or non-actuating circuit of each tube (indicated only for tube V_s as containing resistor R_{23}) is connected to a system of photo tubes P_i , P_d . These are the photo tubes also shown in Fig. 20 in association with flash network N_f . It will be understood that there are, as shown in Figs. 4 to 6, two photo tubes for each operational mark, and that there is a pair of counting photo tubes for each order position.

Each multi-vibrator tube has a load resistor R_{23} . The actuating instrumentalities, in the present instance solenoids Z_{os} , Z_{op} , Z_{su} , and Z_{pu} , etc., are connected between anode a_{22} with terminal 306 and bus A, in circuits containing the switching devices of commutators N_a and N_p and relays Z_{op} , Z_{os} , and Z_{oc} , whose structure was described above and whose function will be described in detail below. It will be evident that, if any tube is conductive through anode a_{22} , the corresponding magnet Z will be energized, whereas switching of conductivity to anode a_{21} will deenergize that magnet.

It should be noted that the photo tubes whose reference characters contain the indicia P_d correspond to the directly illuminated tubes also indicated at P_d in Figs. 4 to 6 and in network N_f of Fig. 20, and that the photo tubes marked P_i are the indirectly illuminated photo tubes, namely those which receive their light from reflecting portions of the record strip 40. With the record carrier 40 reflecting the light beam from lamp F, as indicated in Fig. 20, P_d as well as P_i are illuminated, and point 321 (indicated for photo tubes P_i s and P_d s of the subtracting operational tube V_s) assumes an intermediate potential. The various switches are then set as indicated in Fig. 20, and the counting or clutching magnets are de-energized.

This counting and operational network N_c functions as follows:

When a code of operational marks 41, 42 passes between the detecting ends of rods 70 and 80 (Figs. 4, 5, 6), leading from the flash lamp to the respective P_i tubes, the corresponding P_i tube becomes dark and its impedance increases, whereas the P_d tubes remain illuminated, so that the potential of point 321 rises.

The multi-vibrator tubes V have normally low conductivity. When a photo tube P_i becomes dark for an instant as above described, and the potential of point 321 consequently rises, the left hand section with anode a_{21} of tube V becomes considerably more conductive, resistor R_{23} effects an increased voltage drop thereacross, and grid g_{22} becomes more negative. Capacitor C_1 having been in condition of rest, suddenly sees its left hand side (on R_{23} and a_{21}) drop in voltage. The capacitor being comparatively slow in discharging, its right hand side (on g_{22}) must see the same voltage drop. Grid g_{22} thus has its normally negative voltage and in addition this voltage drop through capacitor C_{21} . The right hand side of the tube (with a_{22}) therefore remains "off." But gradually capacitor C_{21} discharges until its right hand side is at the same potential as the left hand side. This potential being positive with respect to the

cathode, the right hand side with a_{22} becomes fully conductive. With load Z now carrying more current, the potential of grid g_{21} is depressed and the left hand section assumes low conductivity. The right hand section regains normal low conductivity shortly after the first section, upon charge of condenser C_{21} to the point where the potential on grid g_{21} becomes more negative than that of the cathode. The nonconductive state of the right hand side of the tube is however rather unstable since capacitor C_{21} discharges only slowly through R_{21} and the conductive left hand side of the tube until g_{22} again becomes sufficiently positive to render the right hand side conductive. The respective anode potential lowers, a negative pulse is transmitted through C_{22} to g_{21} which

turns off the left hand side establishing the stable condition prevailing at the beginning of the cycle and until the next pulse arrives. Thus, both sections retain their low conductivity until the next impulse arrives, again due to different illuminations of photo tubes P_d and P_i respectively. The relative voltage levels of cathode and grids are due to the voltage drop in cathode bias resistor R_{20} during normally low conductivity of the tubes (when they are for practical purposes nonconductive) which bias resistor R_{20} prevents a continuous oscillation condition.

Connected to the anodes a_{22} of the counting tubes V_u , V_t , etc., are adding solenoids Z_a , and parallel thereto subtracting solenoids Z_s , and printing solenoids Z_p . The other sides of these solenoids are connected to positive bus extensions B_{22} , B_{21} , and negative extension B_{11} , respectively.

The energizing anode of the subtracting tube V_s is connected to positive bus A, through solenoid Z_{os} and extension B_2 . Solenoid Z_{os} operates a switch with contacts s_{51} and s_{52} which normally connects A through B_2 to B_{22} through s_{51} and Z_a , but upon closing of relay Z_{os} connects A to B_{21} and the Z_s clutch magnets.

The energizing anode of totaling and printing tube V_p is connected to positive bus A through solenoid Z_{op} , extension bus B_{22} and contacts s_{51} . Solenoid Z_{op} operates a switch with four contact elements s_{31} , s_{32} , s_{41} , s_{42} which normally connect bus A to A_{32} and bus B with B_{12} , and, with Z_{op} energized, connect A with A_{31} and B with B_{11} .

The solenoids Z_a and Z_s are the clutch solenoids shown and described with reference to Fig. 7; solenoids Z_p are shown in Fig. 16; and solenoids Z_{os} and Z_{op} are the switch or relay solenoids shown in Fig. 8.

The anode of thyratron G_5 leads, in parallel to hammer magnet Z_h , to solenoids Z_{oc1} and Z_{oc2} , one of which is indicated at Z_{oc} of Fig. 8. These solenoids operate switches s_{71} and s_{01} , s_{02} . Solenoid Z_{oc1} operates normally closed contact s_{02} connecting a capacitor C_0 in series with a resistor R_0 across lines B and A1, and normally open contacts s_{01} between s_{02} and solenoid Z_{oc2} . Solenoid Z_{oc2} operates normally open contacts s_{71} for connecting line B1 to line B.

The sequence and counting circuits are correlated by the commutator switches, one for each positional or order tube V_u , V_t , etc. These are the commutator switches described with reference to Figs. 7, 13, 14, 15 and 15a. Their contacts s_1 , s_2 , s_3 , s_4 , and s_{11} , s_{12} , s_{13} , s_{14} are correspondingly indicated in Fig. 20.

Fig. 20 shows the accumulator commutator contacts at N_a , in the position indicated in Fig. 15, with the exception that contact s_{11} is not continued to overlap contact s_1 but broken off, in order to simplify the drawing. Contacts s_1 and s_2 are joined, through condenser C_{49} , to auxiliary bus B1. Contact s_3 is directly joined to B1. Contact s_4 is joined to auxiliary bus B11. Contact s_{11} leads to point 321, between the photo tubes P_{dt} and P_{it} of the next higher order tube V_t ; thus, as shown in Fig. 20, s_{11} of the first commutator is connected to grid connection 321 of the "tens" digit switching tube V_t ; s_{11} of the next or "tens" commutator is similarly connected

to 321 of the "hundreds" tube, and so on. Contact *s12* is connected to bus *A1*. Contact *s13* is connected to auxiliary bus *B12*. Contact *s14* is connected to the grid *g22* of the respective counting tube.

The printing solenoids *Zp* are associated with the printer clutches and commutator switches shown in detail in Figs. 16 to 19. Fig. 20 shows these commutator switches at *Np* in the position of Fig. 19, but with contacts *s22* and *s23* broken off, and contacts *s25* and *s26* somewhat removed from *s22* and *s23*. Contact *s22* is connected to auxiliary bus *B11*. Contact *s23* is connected to auxiliary bus *A31*. Contact *s25* is connected to auxiliary bus *A32*. Contact *s26* is connected to auxiliary bus *B12*. Each accumulator set has a corresponding printing commutator, as explained with reference to Figs. 16 to 19, the two commutator sets being co-related as just described.

Operation

Code system.—In recapitulation, it should be remembered with reference to Figs. 2 and 3, that the code system employed in the present embodiment of my invention comprises the following elements. A record carrier, such as a strip of Celluloid, plastic material, or paper carries for each digit of a number to be fed into the machine a series of counting marks as follows. Each digit, regardless of its order, is made up of a number of, for example four code marks, each of which signifies a certain numerical value. As indicated in Fig. 3, the first (in the direction of the record progress) code mark may denote the number value 2, the next code mark likewise the number value 2, the third code mark the number value 1, and the fourth and last code mark the number value 4. Any desirable number can be made up from these code marks, as indicated in Figs. 2 and 3. Fig. 3 shows the marks for a nine digit number "123456789." It will be noted that digit "1" consists of the third code mark denoting value one, that digit "2" consists of the first code mark denoting value two, etc., the digit "9" being made up of all four code marks adding up to 9. It should especially be noted in this connection, that the code marks employed according to the present invention actually effect adding or counting operations involving the numerical value of the code mark, and are not mere symbols of an intervening operation of translating them into actual numbers.

One side of the code marks, and in the present embodiment extending over the entire length of the four code marks for each number, additional marks are applied to the record, which are herein referred to as operational marks. Such operational marks are for example the "subtracting mark" indicated at 44 of Fig. 2, and, in another column, the "totalling mark" 45. Additional operational marks may be added according to requirements. In accordance with the embodiment herein described, the totalling mark 45 accompanies a totalling code mark which covers the entire code mark area, such as indicated at 48 in Fig. 2.

The record further carries marks which are herein referred to as sequence marks or slits and which may consist of an opaque or non-reflecting strip which carries a series of transparent or non-absorbing areas 43, one in the approximate center of each of the four code marks, and an additional one, number 49, beyond the last code mark row. It will be understood that instead of being clear, these sequence marks may be opaque or non-reflecting, which modification requires a corresponding change in the photoelectric circuit, in conventional manner.

Generally speaking, the sequence marks are placed at designated positions within the item entry or digit code marks. The operational marks are similarly related to the item entries and to each particular mark position upon the record as a whole is assigned a specific function to be performed by the machine when the respective

mark arrives at the detecting element in corresponding position.

It should be understood that the above described marking system is optional, and that any system may be used which is able to perform the functions according to the present invention as herein described.

Normal condition.—Under normal conditions, all electro magnets are de-energized. Consequently, the counting shafts are stationary, and the counter disk and switching armatures rest on their permanent magnets.

10 The exciter lamp *E* is illuminated, whereas the flash lamp *F* is dark.

The gas filled tubes *G1* and *G4* of the sequence circuit *Ns* are non-conductive, tube *G5* is conductive upon passing 15 of the last slit of a group of sequence marks 43, and both sections of each counting and operational tube *V* of counting circuit *Nc* are likewise non-conductive. Both detecting and compensating photo tubes *Pd* and *Pi* of the counting circuit are in high impedance condition.

20 *Accumulating (adding).*—A record strip 40 has been inserted and, driven by motor 55, moves at constant speed through the machine. The sequence trigger tube *Pt* is periodically illuminated by light coming from lamp *E* through the light conductors 91 and 92 shown in Figs.

25 5 and 6, once for each sequence slit 43. As above described, consecutive illumination of photo tube *Pt* triggers the thyratrons *G1* to *G5* in sequence, with a slight time delay relatively to the flashing of lamp *F*, caused by the circuit *C4*—*R4*. Assuming that the time elapsing

30 between the passing of the first sequence slit to that of the last slit 49 of a group takes 20 time units, the slits follow each other in intervals of five time units so that each gas tube remains conductive during five time units. The solenoids operated from the sequence tubes *G1* to

35 *G5* require, in the present embodiment, energization times of two, two, one, four and one time units, respectively. It will thus be seen that these solenoid operation times fit easily within the time intervals elapsing between the effectiveness of consecutive slit marks. It should further

40 be noted that, as mentioned above, the flash lamp *F* becomes effective prior to energization of the sequence solenoids. Consequently, the counting or multi-vibrator tubes *V* become energized prior to conductivity of the sequence tubes, so that for each row of marks, the counting circuits are set up by the multi-vibrator tubes prior

45 to energization of the respective thyratrons, as indicated in Fig. 3. By means of properly dimensioning the conventional timing circuits of the multi-vibrators, the clutch and relay magnets are retained in energized condition during a time period covering the shifting operation of stepping solenoids *Z1*, *Z2*, *Z4*.

In order to understand the operation of the shaft rotating mechanism, it should be remembered that the sequence solenoids *Z1*, *Z2*, *Z4* are coordinated to the sequence tubes *G1* to *G5* as follows:

50 The first sequence tube *G1* is connected to solenoid *Z2* which, as above described, rotates, when energized, the shaft 105 (Figs. 7, 8, and 9) by way of the armature of solenoid *Z4*, through an angle of 72° which defines the

55 number value "two" and corresponds to the first code mark. The sequence tubes *G2* and *G4* are connected to solenoid *Z4* which, as above described, is so arranged that it turns, if solenoid *Z2* is energized at the time of energizing *Z4*, the shaft 105 through an angle defining the number value "two" whereas if not limited by sole-

60 noid *Z2*, it turns the shaft through an angle of 144° defining the value "four." The sequence tube *G3* is connected to solenoid *Z1* which is adapted to rotate shaft 105 through an angle of 36° defining the number value "one."

70 As above described, tube *G5* is connected to a solenoid *Zoc* which operates the switch *s71* for connecting line *B* to the commutator switches *Na*. Tube *G5* is further connected to solenoid *Zh* which operates the printer hammer.

75 While the accumulator solenoids *Z1*, *Z2*, *Z4* are directly

connected to line A, the hammer solenoid Z_h and the printer solenoids Z_{p1} , Z_{p2} and Z_{p4} are connected to an auxiliary bus A31, which leads to contacts $s31$ of switch Z_{op} , as above described. It will be remembered that the accumulating solenoids $Z1$, $Z2$, $Z4$ are energized every time one of the first four slits 43 passes light through conductors 91, 92, rendering photo tube P_t more conductive, and, with some time delay caused by network R4, C4, rendering the tubes $G1$, $G2$, $G3$, $G4$ and $G5$ consecutively conductive; the multi-vibrator tubes V which operate the accumulating magnets are energized somewhat before the sequence solenoids become active.

Observing now for example the accumulation of number "56789" as shown at 41 of the record strip 40 of Fig. 2, it will be noted that the first two code marks of the order or column defining digit "5" are blank so that, although the first two sequence slits will operate solenoids $Z2$ and $Z4$ respectively and correspondingly rotate the shaft 105, the coupling magnets of the "ten thousand" set of the accumulator will not respond and the corresponding accumulator disks will remain stationary. The third code mark of the "ten thousand" column will render its tube V conductive, and the third slit will shortly thereafter energize sequence solenoid $Z1$. The rotating shaft 105 thus finds the tens of thousands order counting disk connected thereto, and since solenoid $Z1$ defines the unit 1, the counting disk will be advanced one step, through 36° . The code mark of the next row similarly affects the "10,000" counting tube and the corresponding fourth slot energizes sequence solenoid $G4$, causing the accumulator disk to advance four number values. This, together with the previous single step, defines the digit "5." Similarly, the digit 9 in the "unit" position of the above referred to number "56789" will be accumulated by consecutive energization, four times, of counter coupling magnet which connects the corresponding accumulating disk to shaft 105 each time one of the three sequence solenoids rotates the shaft, so that the disk will be advanced first two number values, then again two values, then one value, and then finally four values, together nine values. In this connection it should be remembered that solenoid $Z2$ is energized immediately prior to energization of solenoid $Z4$ and that $Z2$ is not deenergized until $Z4$ becomes energized. Thus the stroke of the actuator moved by solenoid $Z4$ will start from the point to which it was previously advanced by solenoid $Z2$, and this energization of $Z4$ therefore effects but a two step advance of shaft 105.

The above discussed steps are defined by the position of the accumulator disk 145 (Fig. 7), with regard to that of the home or zero point of the subtracting or reference disk 146.

It will be noted that for the above described "adding" operation, the switch Z_{os} is in the position shown in Fig. 20, with contacts $s51$ closed, and contacts $s52$ open. Switches Z_{op} and Z_{oc} are likewise in the position shown in Fig. 20. The commutator contacts of the several accumulating sets move relative to each other, but this movement has significance only when the nine to zero region of the accumulator disk 145 coincides with the home point of the reference disk 146, as will be presently explained.

Accumulating (subtracting).—For subtracting, the above described apparatus utilizes a novel procedure which is illustrated in Figs. 21, 22, and 23, and the general principle of which will now be described.

This subtracting method is based on the concept of a "floating home" or "advancing zero" position of the subtracting and reference element. Fig. 21 shows an adding element 345 and a subtracting and reference element 346 in normal position. In this position, the zero point of the adding element 345 coincides with the home or zero position h of the reference element 346. For the accumulating or adding of numbers or, generally speaking, of digits of a notation, element 345 is advanced in the

direction of the arrow shown in Fig. 22. For example, in order to accumulate the number "four," element 345 is advanced four steps until the point defining four coincides with the home point h of element 346. If another number, for example three, is to be added, the element 345 is advanced another three steps, until the point defining seven coincides with h of 346. If it is desired to subtract a number, the element 346 is advanced in the same direction which was used in advancing strip 345 for carrying out accumulating or adding operations. Thus, if it is desired to subtract three from four, as illustrated in Fig. 23, strip 346 is advanced three steps in the direction of the arrow, so that number one of strip 345 now coincides with floating mark h of element 346.

It will be evident that this subtracting method can be carried out with elements of any desired type. If, for operations with small numbers, straight elements are used, the numbers have to be repeated several times; for most applications, round computing elements will be used, each divided into ten parts defining the ten digit values. Apparatus of this type is illustrated in the present computing machine, where elements 145 and 146 (Fig. 7) correspond to elements 345 and 346 of Figs. 21 to 23.

If the computation results are to be mechanically or otherwise recorded some means have to be used for rendering the mechanical position of the floating zero or home independent of its actual meaning with regard to the computing operations. The apparatus according to the present invention exemplifies such an arrangement in the commutator arrangement particularly illustrated in Figs. 13, 14, 15 and 15a. As will be described hereinbelow more in detail, this arrangement permits detection and evaluation of the relative position of the counting elements, independently of their mechanical relation to the physical structure of the apparatus.

One possibility, likewise in accordance with the present invention, of subtracting by means of the floating home method will now be described.

The subtracting operation is initiated by means of a subtraction defining operational mark 44 (Fig. 2), which operates in the above described manner the subtracting tube V_s , by means of photo tubes P_{ds} and P_{is} and their light conductors as shown in Figs. 4, 5, 6, and 20. Referring again to Fig. 2, the subtraction mark 44 indicates that the number "00536" is to be subtracted from the sum of the previously handled numbers. When, during the flash from lamp F, mark 44 renders photo tube P_{is} less conductive than P_{ds} , tube V_s becomes conductive through anode $a22$ and energizes solenoid Z_{os} . This solenoid then disconnects, at $s51$, the adding solenoids Z_a from line B and connects instead at $s52$, the subtracting solenoids Z_s . It will be noted that mark 44 (Fig. 2) triggers tube V_s five times, each time when a flash due to passing of one of the five corresponding slits 49 occurs. The control circuit of tube V_s is so adjusted, according to well known principles as explained above, that the tube section containing anode $a22$ remains conductive throughout the passing of mark 44. The values of capacitors $c21$ and $c22$ for tubes V_s and V_p and hence their discharge times differ from those of the corresponding capacitors of tubes V_u , F_t , etc. The former correspond to the length of the operational indicia 42 (Fig. 2) whereas the latter correspond to the length of the code marks. At the same time, the first code mark, for example the mark defining value "two" as the first component of number six in the above mentioned number "00536," energizes the unit position solenoid Z_{su} , thus attaching the respective subtracting and floating home element 146 (Fig. 7) to shaft 105. Thereupon, the first sequence slot 43 renders tube $G1$ conductive, energizes solenoid $Z2$ which shifts the subtracting element two units. The next two code marks are empty, but the fourth causes a shift of four values, completing the number six. Similar operations simultaneously take place for the digits in the higher positions. After the entire num-

ber to be subtracted has thus been evaluated, the end of mark 44 causes tube V_s to switch its conductivity back to normal effectively non-conductive condition, deenergizing solenoid Z_{05} and conditioning the circuit for connecting the adding clutch magnets Z_a instead of the subtracting clutch magnets Z_s . If a further number is to be subtracted, its code marks would again be accompanied by a subtracting mark 44, which would maintain the subtracting clutch magnets in operation, and again cause the subtracting and reference disks 146 to be attached to shaft 105, instead of the adding disks 145.

It is again emphasized that in accordance with my new subtracting principle, both adding and subtracting elements move always in the same direction, as pointed out above when relating the movement of disks 145 and 146 to shaft 105, which, of course, is rotated always in the same direction by solenoids Z_1 , Z_2 , and Z_4 .

The reference point, namely point 0 of disk 146 (Fig. 14), rotates in the same direction around shaft 105, but the relative position of the adding and subtracting elements or disks is evaluated by means of the commutator, whose operation will be described in detail hereinbelow, under the heading "Total Taking." It will also be noted that the possibility of actuating the adding and subtracting disks by the same stepping solenoids, is due to the fact that they move in the same direction.

Carry-over.—As well known, a carry-over operation has to take place whenever an accumulating element moves from its position 9 to its position 0 relatively to the zero or home point. In the present instance, where co-directionally moving counting elements are used for algebraic summation as well as for defining the home point, the carry-over operation has to take place whether due to movement of the positive, that is adding, or the negative, that is subtracting and reference disk. Whenever the point 9 of an adding disk is about to move to bring the zero point of that element into coincidence with the floating home point of its reference and subtracting element, whether this is due to the movement of the adding or the subtracting disk, a carry-over operation must be carried out for bringing about a change of digit value "one" in the next higher order. There is, however, one distinction, namely this change of one value in the next higher order has to be an increase when caused by an adding operation in the lower order, but decreased when due to a subtracting operation in the lower order.

In the present embodiment of my invention, the carry-over operation is carried out by means of the commutator construction shown in detail in Figs. 13 to 15a. The correlation of the two commutator disks 145 and 146, in normal or starting condition for a carry-over, is indicated in Fig. 15, which is repeated in the circuit diagram of Fig. 20, the latter, however, not showing the entire contact s_{11} , although the continuity of that contact is indicated by joining its broken off end, shown in Fig. 20, to point 321 of the next higher group of circuit N_c . The carry-over operation is first set up for each unit in which the above described progress from "9" to "0" takes place, but it is actually carried out by means of the capacitor indicated at C_{40} of Fig. 20.

Referring to Figs. 13 to 14, it will be noted that the commutator contacts s_1 and s_2 of disks 145 are electrically connected and normally in contact with contact s_{11} of the reference disk 146 which contact s_{11} is only interrupted through the partial length of one unit, following the position of the home or zero point. As indicated in Fig. 20, the contact s_{11} is at 321 connected to the grid of the clutch switching tube of the next higher group, contact s_{11} of the "units" set being connected to 321 of "tens" tube V_t , whereas the contact s_{11} which goes with V_t is analogously connected to the grid of tube for the "hundred" digits, and so on. Normally (that is excepting the period from the time when point "nine" of the adding disk passes from the "home" point of the

other element, until point "zero" of this adding element reaches the "home" point) capacitor C_{40} is enabled to discharge through the connection $s_1-s_2-s_{11}$. The complete discharge circuit of capacitor C_{40} is $C_{40}-s_{11}-321-Pit-B-s_{72}-C_{40}$. Fig. 15 shows the superimposed commutator disks (seen from one side as if transparent and hence rotating in the same direction as indicated by the arrows) in the "adding" position when point nine of the adding disk 145 (Fig. 13) coincides with the home point of the subtracting disk 146 (Fig. 14), further rotation of the adding disk bringing both zero points into coincidence. Contact s_3 of the adding commutator disk is normally open when the point "nine" of that disk reaches "home." After point 9 of the adding disk passes "home," s_1-s_2 become disconnected from s_{11} and instead connected to s_{12} (on bus A). At the same time the normally open commutator contact s_3 is connected to commutator contact s_{13} of the other disk which is through contacts s_{42} connected to the bus B, with relay Z_{op} in the normal position shown in Fig. 20. It should be noted that capacitor C_{40} is normally disconnected from line B by switch s_{71} which is operated by condenser C_0 under control of solenoid Z_{oc1} . This solenoid Z_{oc1} is energized when stepping tube G_5 becomes conductive, due to the effect of the fifth sequence mark 49. With commutator contact s_{13} thus connected to the negative bus B, and with commutator contacts s_1-s_2 connected to the positive bus A, capacitor C_{40} charges in circuit $s_{12}-C_{40}-s_3-B_{12}-s_{42}$. The disks 145 and 146 continue their relative movement until contact s_3 of adding disk 145 again leaves contact s_{13} of reference disk 146, so that capacitor C_{40} is now disconnected from the negative bus B, retaining its charge. With the two commutator disks 35 further continuing their relative movement, contact s_1 and with it contact s_2 comes into contact with s_{11} of the reference disk just before the "0" position of adding disk 145 reaches "home" position of disk 146. This position is shown in Fig. 15a.

Keeping in mind that condenser C_{40} is still charged, the fifth sequence slit 49 now renders the fifth sequence tube G_5 conductive, energizing relay Z_{oc1} of the carry-over unit, causing Z_{oc2} by discharge of condenser C_0 to close contacts s_{71} , and putting capacitor C_{40} on the negative bus B. The capacitor C_{40} thus adds its charge to that of bus B, putting it on the grid of the non-conducting side of the next higher counting tube V_t which thereupon connects the corresponding clutch magnet. Slit 49, through tube G_5 , also energizes magnet Z_1 from A_{32} which shifts the stepping solenoid Z_1 , and shaft 105, one step. This is effected by slit 49 triggering G_5 which closes relay Z_{oc1} direct and Z_{oc2} by discharge of condenser C_0 thus putting a negative potential on C_{40} , causing this to discharge and applying a more positive potential to the grid of V_t . Both clutch magnet and shifting solenoid being thus actuated, the carry-over operation of adding one step to the next higher adding element is performed. It should be noted that the carry-over operation is prevented during the "totalling" and "printing operations," to be described hereinbelow, due to the fact that during these last mentioned operations, contacts s_{42} and s_{32} of relay Z_{op} are open.

The above description of the carry-over operation refers particularly to the situation when during an adding operation the adding element 145 progresses from its point nine to its point zero, on the floating home point of the reference element. The corresponding situation occurs in the case of subtraction when the home point of the subtracting disk leaves the zero point of the adding element 145 and progresses to the nine point of its adding element. So far as the relative positions of the commutator contacts s_1 , s_2 , s_{11} and s_{12} and s_3 and s_{13} are concerned, there is no difference between the two situations, the commutator being in effect symmetrical, no matter whether s_2 and s_3 approach s_{13} and s_{12} from

one side or the other. It will be remembered that Fig. 15 shows the superimposed commutator switch disks in the "adding" position when point nine of the adding disk coincides with the home point of the subtracting disk, further rotation of the adding disk bringing both zero points into coincidence. On the other hand, assuming that the relative position of the disks is as shown in Fig. 15a, the adding disk is stationary and the subtracting disk advances (in the same direction), the relative position of the commutator contacts at the start is that indicated in Fig. 15a, which shows that, as above stated, the relation of the contacts is for present purposes the same.

However, since switch *s52* of solenoid *Zos* has during the subtracting operation, connected the subtracting clutch magnets instead of the adding clutch magnets, the subtracting disk instead of the adding disk of the next higher order is turned one step, reducing that order by one digit, which is the proper operation in the situation.

It will be noted that, as explained above under "accumulating (subtracting)," the subtracting switching tube *Vs* remains conductive for energizing its clutch magnet throughout the time period when the effect of the fifth sequence slit prevails, because the subtracting operational mark extends over all five sequence slits triggering the tube at the passing of each sequence slit, so that any carrying-over operation in a subtracting step is properly finished without premature interruption.

One operational mark which initiates and controls subtracting is of sufficient length to provide for successive carryover operations, as in the instance where a first carry-over step will cause simultaneously minus carry-over operations in a multiple of orders positioned to the left of that first order, as in the case of the so-called "fugitive one" which will now be discussed somewhat more in detail.

The fugitive one has to be taken into account when a number added is greater than the capacity of the machine.

For example, if the total in the accumulator is 150 and the number 224 is to be subtracted therefrom, the customary computing machine will indicate as a result the so-called "complement number," from which complement number the correct result has to be derived by subtracting it from . . . 9999. In the present instance the complement number would be 9925 which, subtracted from 9999 gives the correct result, minus 74. In other words, if the conventional method of subtracting by reversal is used, and continued for a negative total after the 0000 position is reached, there will always be alternative total designations, namely 0000 if the operation is in addition, and 9999 if the operation is a subtraction.

Another example of the fugitive one occurs in the instance where the addition of a number to a previously recorded number results in a sum which is higher than the remaining capacity of the apparatus. For example, if the number 224 is to be added to the complement 9925, noted above, the hundreds wheel in turning through nine to zero will be reason of its carry-over cause the order next to the left to turn through nine to zero and so on through the *n*th order. The *n*th order in turn will cause a carry-over operation of the unit order so that the result will read 159, which is correct.

This fugitive one is dealt with in accordance with my present invention in the following manner.

The sequence tube *G5* does not directly energize solenoid *Z1* which performs the single step shift of shaft **105**, for the carry-over operation, but this solenoid *Z1* is instead, for the said carry-over operation, energized by relay *Zoc2* under the control of condenser *Co* which also triggers the corresponding clutching tube *V*. When now, for example during the above mentioned adding of "224," the "hundred" disk **146** turns two number values, from "9" to "one," its carry-over commutator switch charges condenser *C40*; at this instant no carry-over count takes place on the thousand wheel. When the fifth sequence tube *G5* becomes conductive, *Zoc1* is ener-

gized and the closing of contacts *s01* causes condenser *Co* to discharge, energizing solenoid *Zoc2* and closing switch *s71*. Solenoid *Zoc2* being now under the control of condenser *Co* it can remain energized only during the period while *Co* has a charge. This period is regulated for example by selecting the condenser rating and coincides with the length of time solenoid *Z1*, after being energized by the firing of *G1*, takes to move drive shaft **105** through 36 degrees. The circuit from tube *G5* is delayed long enough by resistor *RZ* before energizing solenoid *Z1* so that the functioning of solenoid *Z1* will coincide with the discharging of the *C40* condensers associated with the affected orders of the *V* tubes. It will be explained below how the "carry-over" and "carry-on-carry" operations of all affected orders are performed simultaneously. Solenoid *Zoc1* remains energized as long as tube *G5* is on, whereas conductivity of tube *G5* has no effect upon solenoid *Zoc2*.

The opening of contacts *s71* at the actual ending of the *Z1* stroke prevents the firing of the *V* tubes during the period while tube *G5* remains on and thus prevents any *C40* condensers that might have been charged during a "carry-on-carry" operation from discharging during the same period of *G5* in which the "carry-on-carry" was originated, thus causing the coincident *V* tube to be fired at a period when drive solenoid *Z1* is not moving shaft **105**.

When another "carry-over," termed a "carry-on-carry" is originated by the recording operation of a "carry-over," this "carry-on-carry" cannot immediately be recorded because contacts *s71* have been opened by *Zoc2* as noted above. The initiating impulse to record this "carry-on-carry" is stored in condenser *C40* until the moment tube *G5* is fired in the next cycle of tubes *G1* to *G5*. The "carry-on-carry" operation of all affected orders taking place simultaneously eliminates the necessity for repeat firings of *G5* and therefore a repeated energizing of *Z1* during a single cycle of tubes *G1* to *G5*.

The simultaneous "carry-over" and "carry-on-carry" operations performed simultaneously with one and the same machine operation, as follows.

Coincident with each order position are two switching contact arrangements, one for the normal "carry-over" operation and the other for the "carry-on-carry" operation. Whenever a condition has been set up in an order or orders that calls for a "carry-on-carry" operation, that is a condition that shows figures such as 39992, then, when the next "carry-over" operation in the digit order next to the right of the nines orders takes place, both the "carry-over" and the "carry-on-carry" operation of all affected orders will be performed simultaneously regardless of the number of "carry-on-carry" orders in sequence to the left of the "carry-over" orders that show the digit 9 in sequence.

For that purpose, a contact *s5* is located on the face of commutator switch disk **145** (Figs. 13 to 15a) at its "9 count" at the "home" or "zero" position on disk **146** the contacts *s5* and *s15* are in contact one with the other. These two contacts will remain in circuit making relation so long as they are in this relative position.

The contact *s5* on disk **145** is electrically connected from the condenser *C40* through switch *s1* on one order, to the contact *s11* on the next order to the left which leads to point **321** on the grid circuit of the second order to the left. If in this sequence the second order to the left also shows a "9 count" then this same circuit will establish a through connection to the third order to the left.

As an example let it be assumed that the orders read 39992 and that the unit digit "8" is to be added to this sum of 39992. The operation of adding the digit "8" will cause the following simultaneous operations.

The digit "8" will first initiate a normal "carry-over" operation thus causing the condenser *C40* to discharge after the counting disk in the unit order has come to rest

upon passing the "0 count" position. It should be noted that if the problem had been to add the digit "9" instead of "8," then the condenser would have delayed its discharge until the counting disk has come to rest upon passing the "1 count" position.

The discharge of condenser C40 will pass current to the point 321 associated with the grid of the "tens order" V tube by means of line s11 thus causing this "tens order" tube V to read "0." Now because the "9" contacts on the next two orders to the left of the tens order also read "9," the operation coincident with the tens order will take place simultaneously for these two orders. This means there is a simultaneous operation of adding "1" in the tens, hundreds, thousands, and ten thousands orders, thus changing the reading at the start of the problem from "39992" to "40000" by a single mechanical "carry-over" operation, of course, in addition to the simple recording of the digit "8" in the unit order.

If the problem had been one of subtraction instead of addition, then the "carry-over" function would have been performed by a single mechanical operation of deduction instead of addition, in all orders simultaneously. This same operation takes place when a "carry-over" is called for in the "nth" order, in which instance it causes an increase of the digit "1" value in the unit order.

Total taking and printing.—The totalling and printing operation is initiated and controlled by the totalling operational mark 45 of Fig. 2, which coincides with code marks filling the entire code mark area, as indicated at 48 of Fig. 2. This operational mark operates the phototube combination Pdp and Pip, rendering anode a22 of tube Vp conductive and energizing relay magnet Zop, which disconnects the carry-over solenoid magnet Zoc and contact segment s13 of the carry-over commutators, connecting instead, through auxiliary bus A31 the printing solenoids Zp1, Zp2, and Zp4; relay Zop also connects, at s41, the extension bus B11 to main bus B. The subtracting operational mark having become ineffective, switching tube Vs has likewise become ineffective, magnet Zos is de-energized and its contacts back in the position shown in Fig. 20. Due to this provision, the printer solenoids are energized only when called for by the totalling operational marks.

It will be noted that the above energization of magnet Zop also puts the hammer magnet Zh into the anode circuit of sequence tube G5, thus making it ready for operation. The remaining contacts s41 of magnet Zop put the printing clutch magnets Zp on bus B, so that the printer is now fully ready for operation.

It will be noted that disconnection of contact s42 of magnet Zop blocks any carry-over operation during totalling, and also blocks any circuits through printer commutator contacts s26, of commutators Np. This condition is maintained so long as the totalling switching tube Vp conducts through anode a22, so that interference with the operation of resetting the printer and accumulating wheels is prevented.

As pointed out above, magnet Zop has now disconnected solenoid Zoc, in the circuit of sequence tube G5.

It will be remembered that the printing unit above described with reference to Figs. 16 to 19, has type wheels whose numbers run in a sense opposite to that of the corresponding numbers of the accumulator or adding wheels, for the purpose which will presently become apparent.

Since for totalling all code marks are black on the record strip, and since the printer solenoids and clutch magnets are now in circuit, together with the accumulator clutch magnets and solenoids, all these are simultaneously energized during the totalling operations.

With the type wheel in position "normal," the printer commutator contacts s25, and s26 of disk 233 are disconnected, resting in the space between the contacts s22 and s23 of the contacts of the opposite commutator disk 233 (Figs. 16 to 19).

It will now be evident that, with all code marks effective, and with the operational mark "printing" retaining the printing tube Vt conductive to energize magnet Zop, all adding disks and all printer wheels will advance due to the action of the solenoids Z1, Z2, Z4 and Zp1, Zp2, Zp4 rotating shafts 105 and 205 (Figs. 7, 8 and 16). This movement will continue until any one adding disk reaches its home position on the subtracting or reference disk. Then, commutator contacts s4 and s14 of accumulator disks 145 and 146 of the respective set, make connection. Commutator segment s4 leads to the minus bus B through contact s41 of solenoid Zop which is now closed, and commutator segment s14 connects to the grid g22 of tube Vu, or that V tube whose accumulator disk has reached the above mentioned home position. This immediately puts the grid on the negative bus B and renders the respective anode circuit non-conductive, cutting out the respective clutch magnets Za, Zp. Therefore, the respective printer wheel and accumulator disk will immediately stop. It should be noted that this stoppage is independent of the movement of the shifting solenoids Z1, Z2, Z4, Zp1, Zp2, Zp4, which may continue to move if the solenoid in question happens to be one which defines more than one unit, such as solenoid Z4 or Zp4 which, after having brought its accumulator or printer into zero position, might continue to advance through an angle of 108°, representing three number values.

Thus, assuming that any accumulator wheel was, when the totalling operation began, with its point n at the homing position, it will have turned 10-n steps before it comes to the above described stop, whereas the printer wheel, being inversely numbered, but turning in the same direction, will stop at n, that is the correct position for totalling and recording the total. All wheels whose zero adding wheel point has reached the home point of the subtracting or reference wheel, are locked by the circuit through the segments s4—s14 of their commutators.

While, as mentioned above, the sequence solenoids complete their action regardless of the energization or de-energization of the respective clutch magnets at the reaching of the home position of any one zero point of the adding wheel, the fifth sequence slit, operating tube G5, energizes the hammer solenoid Zh, energizing the hammer 211 (Fig. 16) and printing the ledger card inserted in slit 212 of the cabinet as shown in Fig. 1.

The above operation leaves the accumulator disks with all zero points at home position, but not the type wheels.

Type wheel re-setting.—The operation of re-setting the type wheels is performed without the aid of operational or other marks, by means of the printer commutators shown in Figs. 17 to 19. The space between two sets of five sequence slits provides sufficient time for this operation.

Referring now particularly to Figs. 16 to 20, it will be noted that normally, that is before the totalling operation begins, the commutators contacts s25 and s23 of the commutator disks, as shown in Fig. 19. As mentioned above, with the total switching tube Vp conducting through anode a22, contacts s32 and s42 of solenoid Zop are disconnected, and with them the commutator contacts s25 and s26, the latter being kept open so long as tube Vp is conductive as above described, that is, until an accumulator wheel zero point reaches home position. When, after the totalling operation is performed, the tube Vp becomes ineffective because conductive through the non-operative anode a21 and Zop de-energized, connection is made through s22, s23, s26, s25, which are now in contact since the printer wheels are not in the zero position, which alone corresponds to contacts s25 and s26 being positioned in the gap between the two other printer commutator contacts. This circuit is completed through contacts of relay Zop and through the appropriate connections between the commutator segments s25 and s26, as shown at Np in Fig. 20. It will be further observed that the above position of the printer contacts locks out the printer commutator during the totalling operation.

Now, with s_{25} on s_{23} , s_{26} on s_{22} , and s_{32} and s_{42} of Zop closed, the printer solenoids and clutch magnets are energized directly through the printer commutator, in circuit A— s_{32} —A32— s_{25} — s_{23} —A31—R31— Zpu — s_{22} — s_{26} —B12— s_{42} —B, independently of tubes G and V, advancing the printer wheels step by step until each wheel reaches the zero position, when segments s_{25} and s_{26} become disconnected from s_{23} and s_{22} respectively, and the respective clutch magnets are disconnected. Each printer wheel therefore stops at its proper normal position, namely with the zero type on the printing hammer.

The resistor R31 is inserted in this circuit in order to make it electrically equivalent to the corresponding tube control circuits which are otherwise utilized for energizing the respective clutching and shaft turning solenoids.

The accumulator disks are now with their zero points at the home point of each respective subtracting or reference wheel, the printer wheels are at zero position relatively to the recording device, the required adding, subtracting, carrying over and totalling operations have been performed and recorded, and the apparatus is ready for further operation.

It should be understood that the present disclosure is for the purpose of illustration only and that this invention includes all modifications and equivalents which fall within the scope of the appended claims.

I claim:

1. Calculating apparatus comprising supporting means, a scale member defining digits of a notation, a home member defining a reference position, means for moving said members on said supporting means unidirectionally in predetermined differential amounts corresponding to the digits of the notation only, and means for defining the relative position of said scale member and said reference position of said home member, advancement of one of said members in said direction performing an adding operation defined by the relative position of the two members as defined by said series of digits, and advancement of said other member in said direction performing a subtracting operation likewise defined by the relative position of the two members.

2. Calculating apparatus comprising mounting means, a member defining digits of a notation, a home member having zero indicating means, means for moving said members on said mounting means relatively to each other unidirectionally in predetermined differential amounts corresponding to the digits of the notation only, and means for defining the relative position of said digit defining member to said zero indicating means, advancement of one of said members in said direction performing an adding operation, and advancement of other member in said direction performing a subtracting operation, both operations being defined by the position of the first member relatively to said zero defining means.

3. Calculating apparatus comprising mounting means, a first substantially circular scale member angularly subdivided to define in equal steps digits of a notation, means for rotating said scale member relatively to said mounting means unidirectionally in predetermined differential amounts corresponding to the digits of the notation, a second substantially circular member arranged for rotation concentric with said first member and having zero defining means, means for rotating said second member on said mounting means in similar predetermined differential amounts and in said direction, and means for defining the relative position of said scale member and said zero defining means, rotation of said scale member in said direction performing an adding operation defined by the position of the first member relatively to said zero defining means, and rotation of said second member in said direction performing a subtracting operation likewise defined by the position of the first member relatively to said zero defining means.

4. Calculating apparatus comprising mounting means, a first substantially circular scale member angularly sub-

divided to define in equal steps digits of a notation, means for rotating said scale member relatively to said mounting means unidirectionally in predetermined differential amounts corresponding to the digits of the notation, a second substantially circular member defining a reference position arranged for rotation concentric with said first member, means for rotating said second member on said mounting means in similar predetermined differential amounts and in said direction, and means for indicating the relative position of said scale member and said reference position, rotation of said scale member in said direction performing an adding operation defined by the position of the first member relatively to the second member, and rotation of the second member in said direction performing a subtracting operation likewise defined by the relative position of said members.

5. Calculating apparatus comprising mounting means, a first scale member defining in equal steps digits of a notation, a second scale member having zero indicating means, means for moving said members on said mounting means relatively to each other both unidirectionally in predetermined differential amounts corresponding to the digits of the notation, said unidirectional movement of said first member performing an adding operation defined by the position of the first member relatively to said zero defining means, and said unidirectional movement of said second member performing a subtracting operation likewise defined by the position of the first scale member relatively to said zero defining means, and means for defining the position of said first scale member relatively to said zero defining means independently of the position of said scale members relatively to said mounting means.

6. Calculating apparatus comprising mounting means, a first substantially circular scale member defining in equal steps digits of a notation, a second scale member having zero defining means, means for concentrically moving said members on said mounting means relatively to each other unidirectionally in predetermined differential amounts corresponding to the digits of the notation, said unidirectional movement of said first member performing an adding operation defined by the position of the first member relatively to said zero defining means, and said unidirectional movement of said second member performing a subtracting operation likewise defined by the position of the first scale member relatively to said zero defining means, and means for defining the position of said first scale member relatively to said zero defining means independently of the position of said members relatively to said mounting means.

7. Calculating apparatus comprising mounting means, a first number defining scale member, a second member having zero defining means including a relay circuit having two contact means, one moving with each of said members and adapted to contact the other, and means for moving said members on said mounting means relatively to each other both in similar steps corresponding to said numbers and in the same direction, advancement of said first member in said direction and movement of its contact means in a corresponding relation performing an adding operation defined by the position of the first contact means relatively to the second contact means, and advancement of said second member and of its contact means in said directions performing a subtracting operation likewise defined by the position of the first contact means relatively to the second contact means, independently of the position of said members relatively to said mounting means.

8. A computing machine of the type wherein radiation sensitive detecting means are controlled by records carrying radiation modifying, positionally co-related counting, operational and sequence indicia, comprising a first counting member, a second counting member, actuating means adapted to move stepwise under the control of said sequence indicia, means for coupling said

first counting member to said actuating means under control of and during steps determined by said counting indicia conjointly with said sequence indicia, means for coupling said second counting member to said actuating means under control of and during steps determined by said counting indicia conjointly with said sequence indicia, means controlled by said operational indicia for selecting one or the other of said counting members for coupling to said actuating means, and registering means on each of said counting members directly juxtaposed for defining the relative position of said two counting members.

9. A computing machine of the type wherein radiation sensitive detecting means are controlled by records carrying radiation modifying and positionally co-related counting, operational and sequence indicia, comprising a first counting member, a second counting member, actuating means adapted to advance stepwise in a given direction under the control of said sequence indicia, means adapted to connect said first counting member to said actuating means for advance in a given sense under control of and during steps determined by said counting indicia conjointly with said sequence indicia, means adapted to connect said second counting member to said actuating means for advance in a given sense under control of and during steps determined by said counting indicia conjointly with said sequence indicia, means controlled by said operational indicia for selecting one or the other of said counting members for coupling to said actuating means, and registering means on each of said counting members directly juxtaposed for defining the position of said first counting member relatively to a point of said second counting member.

10. A computing machine of the type wherein radiation sensitive detecting means are controlled by records carrying radiation modifying and positionally co-related counting, operational and sequence indicia, comprising a first counting member, a second counting member, actuating means adapted to rotate stepwise in a given direction under the control of said sequence indicia, means for coupling said first counting member to said actuating means for rotation in a given sense under control of and during steps determined by said counting indicia conjointly with said sequence indicia, means for coupling said second counting member to said actuating means for rotation in said sense under control of and during steps determined by said counting indicia conjointly with said sequence indicia, means controlled by said operational indicia for selecting one or the other of said counting members for coupling to said actuating means, and registering means on each of said counting members directly juxtaposed for defining the position of said first counting member relatively to a point of said second counting member.

11. Computing apparatus of the type which is controlled by a record which carries radiation affecting and positively co-related counting and sequence indicia, comprising means for continuously moving said record through said apparatus, radiation sensitive means for scanning said indicia with the effective scanning period of said counting indicia including that of said sequence indicia, a counting member, actuating means adapted to advance said counting member stepwise solely under control of said sequence indicia, means for coupling said counting member to said actuating means, and initiating means rendered effective under conjoint control of said sequence indicia and said counting indicia for operating said coupling means.

12. Computing apparatus of the type which is controlled by light modifying and positionally co-related counting and sequence indicia, comprising means for continuously moving said record through said apparatus, photo sensitive means for scanning said counting indicia, separate photo sensitive means for scanning said sequence indicia with the effective scanning period of said

counting indicia including that of said sequence indicia, a counting member, actuating means adapted to advance stepwise under the sole control of said sequence indicia, means for coupling said counting member to said actuating means, flash lamp means rendered effective by said sequence indicia for illuminating said counting indicia, and means responsive to said counting indicia when illuminated by said flash lamp for operating said coupling means.

13. A computing machine of the type wherein radiation sensitive detecting means are controlled by records carrying radiation modifying counting and sequence indicia, comprising a counting member, actuating means adapted to advance solely under control of said sequence indicia, means for coupling said counting member to said actuating means, and initiating means rendered effective under conjoint control solely of said sequence indicia and said counting indicia for actuating said coupling means.

20 14. A computing machine of the type wherein radiation sensitive detecting means are controlled by records carrying radiation modifying counting indicia arranged in several columns defining digit position and several rows defining digit value, and carrying several sequence indicia each one arranged to be effective within the effectiveness period of a corresponding one of said rows of counting indicia, comprising a plurality of counting members, one for each of said columns; actuating means adapted to advance predetermined distances in consecutive 25 steps under the sole control of said sequence indicia; means for coupling said counting members to said actuating means; and initiating means rendered effective solely under conjoint control of each one of said counting indicia and the sequence indicium of its row, for actuating said coupling means.

15. A computing machine of the type wherein radiation sensitive detecting means are controlled by records carrying radiation modifying digit counting marks, and similar sequence marks arranged to be effective within 30 the effectiveness period of said counting marks, comprising a counting member, actuating means adapted to advance under the sole control of said sequence marks, means for coupling said counting member to said actuating means, means for rendering said coupling means effective solely upon conjoint radiation modification by both 35 marks, and means for thereafter advancing said actuating means.

16. A computing machine of the type wherein radiation light sensitive detecting means are controlled by 40 records carrying light absorbing digit counting marks, and light absorbing sequence marks arranged to be effective within the effectiveness period of said counting marks, comprising a counting disk, shaft means adapted to advance under the sole control of said sequence marks, clutch means for coupling said counting disk to said shaft means, flash lamp means rendered effective by said sequence marks and arranged for illuminating said counting marks, and means for actuating said clutch means solely under control of said counting marks when illuminated by said flash lamp means.

17. In a computing machine wherein counting members are moved in steps controlled by electrical code impulses, a stepping device comprising a plurality of counting members, means common to all of said counting members and arranged for the independent advancement 45 of any counting member that is coupled to said advancing means, connecting means for selectively coupling said counting members to said advancing means, a plurality of motor means for actuating said advancing means each having a moving member and means for positively determining the travel of said moving member to a value selected by said impulses, and means linking said moving members to said advancing means for moving said advancing means in a given direction an amount proportionate to said code impulse determined travel during

strokes of said moving member in a corresponding direction while rendering the return strokes of the moving member ineffective.

18. Stepping device according to claim 17, further characterized in that two moving members are independently linked to the transporting means, the travels of said members being unequal, and in that said members can be consecutively energized to provide steps of unequal length of said transporting means.

19. In a computing machine wherein counting members are moved in steps controlled by electrical code impulses, a stepping device comprising a plurality of counting members, shaft means common to said counting members and arranged for the independent advancement of each of said counting members, connecting means for selectively coupling said counting members to said shaft means, a solenoid having an energizing coil, an armature and means for positively determining the travel of said armature to a value which is for each travel selected by said impulses, and means linking said armature to said shaft for moving said counting members in a given direction an amount proportionate to said code impulse determined travel during strokes of said armature in a corresponding direction while the return strokes of the armature are ineffective.

20. Stepping device according to claim 19, further comprising an additional solenoid having an armature likewise linked to said shaft means, the travels of the armatures of said solenoids being unequal, and means for simultaneously and consecutively energizing the solenoids to provide steps of unequal length of said shaft means.

21. In a computing machine wherein counting members are moved in steps of which three are unequal controlled by electrical impulses, a stepping arrangement comprising three impulse supplying sources of electric energy; a transporting means; a solenoid having an energizing coil, an armature and means for positively limiting the travel of said armature to a predetermined value; means for linking said armature to said transporting means; a second solenoid having an energizing coil, an armature and means for positively limiting the travel of said armature to a predetermined value which is lower than that of said first armature; means for co-relating said two armatures to limit said travel of said first armature to a lower value, by said travel of said second armature, while permitting full travel of said first armature when said second solenoid is ineffective; and means for actuating said first solenoid alone from one of said sources, both solenoids together from another one of said sources, and said second solenoid from the third source.

22. In a computing machine wherein counting members are moved in three unequal steps controlled by undifferentiated electrical impulses, a stepping arrangement comprising three impulse supplying sources of electric energy; a shaft; a solenoid having an energizing coil, an armature and means for positively limiting the travel of said armature to a predetermined value; unidirectional clutch means for linking said armature to said shaft, a second solenoid having an energizing coil, a floating armature and means for positively limiting the travel of said armature to a predetermined value which is lower than that of said first armature, and means for co-relating said two armatures to limit said travel of said first armature to a lower value, by said travel of said second armature, while permitting full travel of said first armature when said second solenoid is ineffective, and means for actuating said first solenoid alone from one of said sources, both solenoids together from another one of said sources, and said second solenoid from the third source.

23. A computing machine comprising an accumulating member; a reference member; actuating means; means for advancing said actuating means step by step; means for coupling said accumulating member to said actuating

means; a coupling circuit including current responsive means for operating said coupling means; and a reference circuit including means for energizing said coupling means and further including circuit making means attached to said accumulating member and circuit making means attached to said reference member, said circuit making means modifying said reference circuit dependent upon the relative position of said members.

24. A computing machine of the type wherein radiation sensitive detecting means are controlled by records carrying a consecutively effective radiation modifying counting marks and operational marks, comprising an accumulating member; a reference member; actuating means; means for advancing said actuating means step by step; means for coupling said reference member to said actuating means; a coupling circuit including light sensitive means for detecting said marks and current responsive means controlled by said detecting means for operating said coupling means; and a reference circuit including means for energizing said coupling means and further including circuit making means attached to said accumulating member and circuit making means attached to said reference member, said circuit making means modifying said reference circuit dependent upon the relative position of said members.

25. A computing machine of the type wherein radiation sensitive detecting means are controlled by records carrying consecutively effective radiation modifying counting and operational marks, comprising an accumulating member, a reference member; actuating means; means for advancing said actuating means step by step; means for coupling said accumulating member to said actuating means; means for coupling said reference member to said actuating means; a coupling circuit including light sensitive means for detecting said counting marks and current responsive means controlled by said detecting means for operating said accumulating member coupling means; a coupling circuit including light sensitive means for detecting said counting and said operational marks and current responsive means controlled by said second detecting means for operating said reference member coupling means; and a reference circuit including means for energizing said coupling means and further including circuit making means attached to said accumulating member and circuit making means attached to said reference member, said circuit making means modifying said reference circuit dependent upon the relative position of said members.

26. A computing machine of the type wherein radiation sensitive detecting means are controlled by records carrying positionally differentiated orders of consecutively effective radiation modifying counting marks, comprising two accumulating members; a reference member for each accumulating member; actuating means; means for advancing said actuating means step by step; means for individually coupling said members to said actuating means; a coupling circuit for each member including light sensitive means for detecting said marks and current responsive means controlled by said detecting means for operating a respective coupling means; and a carry-over circuit for said members including circuit making means attached to its accumulating member and circuit making means attached to its reference member, said circuit making means including means for modifying said carry-over circuit to energize the coupling means of the higher member when the relative position of said members defines full accumulation within the positional order associated with said members.

27. A computing machine comprising two accumulating members, a reference member for each accumulating member, actuating means, means for advancing said actuating means step by step, means for separately coupling said members to said actuating means thereby defining numerical values through advance of said members, an

actuating circuit for said members including electrical energy storing means for energizing said coupling means, circuit making means attached to said accumulating member, circuit making means attached to said reference member and modifying said actuating circuit through changing contact association with said circuit making means of said accumulating member with changing relative position of said members, said actuating circuit including means for feeding energy to said storing means of said actuating circuit during one of said positions and for discharging it to energize said coupling means in another position.

28. A computing machine of the type wherein radiation sensitive detecting means are controlled by records carrying two orders of substantially simultaneously effective radiation modifying counting marks and for each of said orders a sequence mark—comprising a counting member for each of said orders; actuating means adapted stepwise to advance under the control of said sequence marks; means for coupling said counting members to said actuating means; detecting means for discharging an energy impulse whenever affected by one of said sequence marks; a coupling circuit including a series of electron discharge valves one for each of said counting mark orders, photo tube circuits associated with the control electrode of each of said valves and arranged to respond to said energy impulses as modified by said counting marks, and current responsive means in the output circuits of each of said valves; and initiating means rendered effective by said current responsive means under conjoint control of said impulse and said counting marks for operating said coupling means.

29. A computing machine of the type wherein radiation sensitive detecting means are controlled by records which carry radiation modifying and positionally co-related digit counting marks grouped to define digit position as well as digit value, which records carry operational marks, and which also carry a series of sequence marks each sequence mark being arranged to become effective with counting mark rows of the same value,—comprising two adding members, two subtracting members each associated with one of said adding members, an actuating shaft adapted to advance, under the control of said sequence marks predetermined distances in consecutive steps and only in a given direction, means for separately coupling each one of said adding members to said shaft under control of and during steps determined by said counting marks conjointly with said sequence marks, means for separately coupling each one of said subtracting members to said shaft under control of and during steps determined by said counting marks conjointly with said sequence marks, means controlled by an operational mark for selecting either an adding or a subtracting member for coupling to said shaft, means for defining the digit value defining position of each one of said adding members relatively to a point of its subtracting member, and means for effecting carry-overs from the lower to the higher adding member.

30. A computing machine of the type wherein radiation sensitive detecting means are controlled by records which carry radiation modifying and positionally co-related digit counting marks grouped as to define digit position as well as digit value, which records carry operational marks, and which also carry a series of sequence marks each sequence mark being arranged to become effective with counting mark rows of the same value,—comprising two adding members, two subtracting members each associated with one of said adding members, an actuating shaft adapted to advance, under the control of said sequence marks, predetermined distances in consecutive steps and only in a given direction, means for separately coupling each one of said adding members to said shaft under control of and during steps determined by said counting marks conjointly with said sequence marks, means for separately coupling each one 75

of said subtracting members to said shaft under control of and during steps determined by said counting marks conjointly with said sequence indicia, means controlled by an operational mark for selecting either an adding or a subtracting member for coupling to said shaft, means for defining the digit value defining position of each one of said adding members relatively to a point of its subtracting member, and means controlled by said sequence marks for carrying over digit values for each pair of adding and subtracting members to the pair representing the next higher order.

31. A computing machine of the type wherein detecting means are controlled by records carrying positionally co-related counting and operational indicia,—comprising two counting members each representing a series of digits in a given sequence of a lower and higher order respectively, actuating means adapted singly and unidirectionally to advance said counting members stepwise under control of said counting indicia with the advance directly representing the actual count as determined by the counting indicia, said number sequence being for both counting members the same relatively to said advance; a reference means associated with each counting member and having zero defining means, said reference defining means being adapted to move codirectionally with the respective counting member such that addition and subtraction can be carried out by unidirectional movement of the counting member and the reference element respectively; carry over means for advancing the higher order counting member when the relative position of the lower order counting member with respect to the related zero defining means defines full accumulation; and totaling means controlled by said operational indicia for codirectional resetting advancement of said counting members until each counting member reaches said zero defining means of its reference means.

32. A computing machine of the type wherein radiation sensitive detecting means are controlled by records carrying several positionally differentiated orders of consecutively effective radiation modifying counting marks,—comprising a series of accumulating members; a reference member for each accumulating member; actuating means; means for unidirectionally advancing said actuating means step by step; means for individually coupling a respective reference member to said actuating means; zero defining means movably associated with said reference members such that addition and subtraction can be carried out by said unidirectional advancement as referred to the movable zero defining means, a coupling circuit for each member including light sensitive means for detecting said counting marks and current responsive means controlled by said detecting means for operating a respective coupling means in direct response to said marks for coupling its reference member to the actuating means; and a carry-over circuit for each pair of an accumulating and reference member including circuit making means attached to its accumulating member and circuit making means attached to its reference member, said circuit making means modifying said carry-over circuit to operate the individual coupling means of the next higher member in direct response to said marks when the relative position of said members relatively to said zero defining means indicates full accumulation within the positional order associated with said pair of members.

33. A computing machine comprising several accumulating members, a reference member for each accumulating member, actuating means, means for advancing said actuating means step by step, means for separately coupling said members to said actuating means thereby defining numerical values through advance of said members, an actuating circuit for each pair of members including electrical energy storing means for energizing said coupling means, circuit making means attached to said accumulating member, circuit making means attached to said reference member and modifying said

network, through changing contact association with said circuit making means of said accumulating member with changing relative position of said members, such that energy is stored in said actuating circuit during one of said positions and discharged to energize said coupling means in another position.

34. A computing machine of the type wherein radiation sensitive detecting means are controlled by records carrying consecutive series of several orders of substantially simultaneously effective radiation modifying counting marks and for each of said orders a sequence mark—comprising a counting member for each of said orders; actuating means adapted stepwise to advance under the control of said sequence marks; means for coupling said counting members to said actuating means; detecting means for discharging an energy impulse whenever affected by one of said sequence marks; a coupling circuit including a series of electron discharge valves one for each of said counting mark orders, photo tube circuits associated with the control electrode of each of said valves and arranged to respond to said energy impulses as modified by said counting marks, and current responsive means in the output circuit of each of said valves; and initiating means rendered effective by said current responsive means under conjoint control of said impulse and said counting marks for operating said coupling means.

35. A computing machine of the type wherein radiation sensitive detecting means are controlled by records which carry radiation modifying and positionally correlated digit counting marks grouped to define digit position as well as digit value, which records carry operational marks, and which also carry a series of sequence marks each sequence mark being arranged to become effective with counting mark rows of the same value, comprising several adding members, several subtracting members each associated with one of said adding members, an actuating shaft adapted to advance, under the control of said sequence marks predetermined distances in consecutive steps and only in a given direction, means for separately coupling each one of said adding members to said shaft under control of and during steps determined by said counting marks conjointly with said sequence marks, means for separately coupling each one of said subtracting members to said shaft under control of and during steps determined by said counting marks conjointly with said sequence indicia, means controlled by an operational mark for selecting either an adding or a subtracting member for coupling to said shaft, and means for defining the digit value defining position of each one of said adding members relatively to a point of its subtracting member.

36. A computing machine of the type wherein radiation sensitive detecting means are controlled by records which carry radiation modifying and positionally correlated digit counting marks grouped as to define digit position as well as digit value, which records carry operational marks, and which also carry a series of sequence marks each sequence mark being arranged to become effective with counting mark rows of the same value, 60

comprising several adding members, several subtracting members each associated with one of said adding members, an actuating shaft adapted to advance, under the control of said sequence marks, predetermined distances in consecutive steps and only in a given direction, means for separately coupling each one of said adding members to said shaft under control of and during steps determined by said counting marks conjointly with said sequence marks, means for separately coupling each one 5 of said subtracting members to said shaft under control of and during steps determined by said counting marks conjointly with said sequence indicia, means controlled by an operational mark for selecting either an adding or a subtracting member for coupling to said shaft, means 10 for defining the digit value defining position of each one of said adding members relatively to a point of its subtracting member, and means controlled by said sequence marks for carrying over digit values for each pair of adding and subtracting members to the pair representing 15 the next higher order.

37. A computing machine of the type wherein radiation sensitive detecting means are controlled by records carrying consecutive series of substantially simultaneously effective radiation modifying counting marks and 20 for each of said series of counting marks a sequence mark, comprising a counting member; an actuating circuit including a plurality of electron discharge valves having parallel connected anodes one for each sequence mark of each series and having control electrodes, a 25 photo tube arranged to be affected by said sequence marks, timing networks connected to said control electrodes and arranged for consecutively rendering, upon receiving an impulse from said photo tube, in response to a sequence mark, one of said valves conductive while 30 extinguishing the one previously conductive, and current responsive means in the output circuits of each of said valves; actuating means adapted stepwise to advance under the control of said current responsive means; lamp means controlled by said photo tube to discharge a radiation flash whenever said tube responds to a sequence mark, means for coupling said counting member to said actuating means; and initiating means rendered effective under conjoint control of said flash and said counting marks for operating said coupling means.
